UNITED STATES PATENT OFFICE.

WILLIAM J. NESBITT, OF LOS ANGELES, CALIFORNIA.

HEEL-CUTTING APPARATUS.

1,289,878.

Specification of Letters Patent. Patented Dec. 31, 1918.

Application filed October 11, 1917. Serial No. 196,084.

To all whom it may concern:

Be it known that I, WILLIAM J. NESBITT, a citizen of the United States of America, residing at Los Angeles, county of Los Angeles, State of California, have invented a certain new and useful Heel-Cutting Apparatus; and I do hereby declare the following to be a full, clear, and exact description of the invention, such as will enable others skilled in the art to which it appertains to make and use the same.

This invention relates to improvements in heel cutting apparatus.

One object of the invention is to provide a novel and improved construction in which the cutter is adapted to be moved against the heel so that the heel is pressed directly against the stationary jaw of the shoe holding device in such manner that the heel is securely held in place while being cut and the heel cannot be pushed out of the heel holding device when the cutter is moved against the heel.

A further object of the invention is to provide a novel and improved heel cutting device.

Another object of the invention is to provide a novel and improved construction for the adjustable mounting of the heel holding device.

With the above and other objects in view, the invention may be said to consist in the provision of the novel and advantageous features and in the novel and improved construction, arrangement, and combination of parts as will be evident from the accompanying drawings in connection with the following description of the preferred construction embodying the invention.

In the drawings, Figure 1 is a side elevational view of the improved heel cutting apparatus; Fig. 2 is a plan view of the same; Fig. 3 is a broken sectional view taken on the line 3—3 of Fig. 2; Fig. 4 is a sectional view taken on the line 4—4 of Fig. 2; Fig. 5 is a sectional view taken on the line 5—5 of Fig. 2; and Fig. 6 is an enlarged broken sectional view taken on the line 6—6 of Fig. 4.

The supporting plate or shelf 10 is preferably provided on its underside with the stem 11 whereby it can be mounted on the stand or pedestal 12 which is partly indicated by dotted lines in Figs. 1 and 4.

On the shelf 10 is mounted the plate 13 which latter has thereon the stationary jaw

14 and the movable jaw 15 of the heel holding device. The jaws 14 and 15 are substantially in alinement in a vertical plane, and they are provided with beveled edges 60 14' and 15' adapted to fit in the crease between the heel seat and the heel 16 of the shoe 17. The stationary jaw 14 is suitably fastened to the plate 13; and the jaw 15 is suitably fastened to the lever 18 which latter 65 has its rear end connected by the pivot 19 to the plate 13 and extends upwardly forwardly and is provided with the handle 20 at its forward end. The forward part of the beveled edge of the jaw 14 extends downwardly rearwardly and fits in the crease at one side of the heel 16, and the rear part of the beveled edge 14' fits in the crease around the rear part of the heel 16. The beveled edge 15' of the jaw 15 fits in the 70 crease at the forward part of the side of the heel 16 opposite to that in which the forward part of the beveled edge 14' is fitted.

The heel cutting device consists of the 80 comparatively thin circular saw 21, and the disk 22 which latter is of slightly less diameter than the circular saw 21 and is placed against one side of the circular saw 21 to stiffen the latter and prevent it from being 85 deflected away from the intact part of the heel 16 when a slice is being cut off of the heel 16. The circular saw 21 is preferably of the type ordinarily used for cutting metal, and it preferably has its teeth 23 offset. The 90 disk 22 has its outer edge disposed adjacent to the toothed outer edge of the circular saw 21 so as to act more effectively to brace the teeth 23, and said disk 22 is preferably provided with straight or non-offset teeth 95 24 disposed directly behind the offset teeth 23 so that any tendency of the disk 22 being wedged in the heel 16 is overcome because the disk 22 can cut and thus clear its path through the heel 16 when the latter is being 100 cut by the circular saw 21.

The shelf 10 is provided at its rear end with the bearings 25 and 26 for the shaft 27 to which is pivotally connected the lower end of the arm 28 which extends forwardly 105 upwardly and has at its upper forward end the handle 29. The arbor 30, to which is fastened the circular saw 21 and its stiffening disk 22, is arranged in the bearing 31 on the arm 28 so that the circular saw 21 110 has its axis disposed above the heel holding device in such manner that when the cir-

cular saw is moved by the arm 28 to cut the heel 16 the latter is forced directly against the stationary jaw 14 so that the heel 16 cannot be pushed out of the heel holding 5 device by the action of the heel cutter. The lower rear end of the arm 28 has thereon the extension 32 provided with the slot 33 through which and the slot 34 in the shelf 10 passes the bolt 35. A spring 36 arranged 10 between the washer 37 on the bolt 35 and the underside of the shelf 10 is adapted to retract the arm 28 and normally hold it so that the projection 38 on said arm contacts with the stop 39 on the shelf 10. As shown 15 in this instance the arbor 30 is driven by the spur pinion 40 which is in mesh with the spur wheel 41 which latter is connected to the sprocket wheel 42 which is mounted loosely on the shaft 27 and is operated by 20 the sprocket chain 43.

The plate 13 has on its underside the pivot 44 which passes through the slot 45 in the shelf 10 and is provided with the nut 46 which latter is preferably provided with the 25 handle 47 to easily adjust it in relation to the shelf 10. The plate 13 has thereon the screw 48 which can be turned by its handle 49 to cause the screw 48 to engage the shelf 10 and lock the plate 13 in adjusted position. The slot 45 extends at a right angle 30 to the circular saw 21 so that the plate 13 when unlocked can be moved by the handle 49 to adjust the heel holding device according to the amount that it is desired to cut 35 off of the heel 16. To make a slanting cut through the heel 16 the plate 13 and consequently the heel holding device can be turned by the handle 49 to have heel 16 disposed at the desired angle to the circular saw 21.

40 From the foregoing the construction, manner of use, and the advantages of the improved heel cutting apparatus will be understood by those skilled in the art.

The construction which has been particularly illustrated and described admits of minor changes and modifications wherefore the right is reserved to all such changes and

modifications as do not depart from the spirit and scope of the invention which is defined in the appended claims.

50 I claim:

1. In a heel cutting device, the combination with a thin circular saw having offset teeth on the outer edge thereof, of a disk placed against one side of said circular saw 55 to stiffen the same, said disk being of slightly less diameter than that of the circular saw and having on its outer edge straight teeth which are disposed adjacent to the offset teeth for the purpose of preventing wedging.

2. The herein-described heel cutting apparatus, consisting of a heel cutting device, a shelf having a slot extending at a right angle to said heel cutting device, a plate 60 mounted directly upon said shelf, a pivot on the underside of said plate, said pivot extending through said slot, and means on said plate adapted to lock the plate in adjusted position on said shelf.

70 3. In heel cutting apparatus, the combination of a shelf, an arm having its rear end part pivotally connected to said shelf and extending forwardly upwardly, a heel holding device carried by said shelf and including a stationary jaw having a beveled edge adapted to fit in the crease between the heel seat and the heel of a shoe, the forward part of said beveled edge having an inclination downwardly rearwardly, and the rear part 75 of said beveled edge being adapted to fit in the crease around the rear part of the heel, and a circular saw mounted on said arm and having its axis above the stationary jaw in such manner that the heel is forced against 80 the said stationary jaw so that the heel cannot be pushed away from said stationary jaw by said circular saw when the latter is moved against the heel to cut the heel.

85 In testimony whereof, I have signed my name to this specification at Los Angeles, county of Los Angeles, State of California, this 1st day of October A. D. 1917.

90 WILLIAM J. NESBITT.
